UNITED STATES PATENT OFFICE.

VICTOR G. JENSEN, OF CHICAGO, ILLINOIS, ASSIGNOR TO C. H. & D. ELECTRIC COMPANY, OF CHICAGO, ILLINOIS, A CORPORATION OF ILLINOIS.

ELECTRIC IRON AND STAND.

Application filed November 8, 1923. Serial No. 673,569.

To all whom it may concern:

Be it known that I, VICTOR G. JENSEN, a citizen of the United States, and resident of Chicago, county of Cook, State of Illinois, have invented certain new and useful Improvements in Electric Irons and Stands, of which the following is a specification.

This invention relates to electrical sad-
10 irons or the like and especially to an auto-
matic electric switch stand for heating such
irons. More particularly the invention aims
to provide a heating stand which is simple
in construction having electrical switches
actuated by the weight of the iron to close
15 a circuit through the iron when the same is
placed on the stand and operated by gravity
to break the circuit when the iron is lifted
from the stand. The invention further aims
to provide a mechanism of this kind in which
20 the movable switch elements are made strong
and durable and easy to manufacture, re-
quiring little or no machine work or skilled
labor, thus greatly simplifying and cheapening
25 production. The foregoing and other
advantages of the invention will be apparent
from the construction hereinafter de-
scribed and which is illustrated in the ac-
companying drawings forming part of this
specification.

30 In said drawings:

Figure 1 is a plan view of the improved
heating stand;

Figure 2 is a transverse section on the
line 2—2 of Figure 1, this view showing one
35 iron in position on the stand;

Figure 3 is a detailed view showing part
of the internal construction of the iron, par-
ticularly the arrangement for holding the
contact plugs in the iron;

40 Figure 4 is a longitudinal section substan-
tially on the line 4—4 of Figure 1, this view
showing parts of the iron and parts of the
stand in section;

45 Figure 5 is a perspective view of one of
the gravity actuated switch elements used
in the stand;

Figure 6 is a detailed sectional view on
the line 6—6 of Figure 2;

50 Figure 7 is a sectional view on the line
7—7 in Figure 3 showing further details of
the means for fastening the contact plugs
in the iron;

55 Figure 8 is a diagrammatic view showing
the contacts and the circuits through the
stand and the iron placed thereon.

In the accompanying drawing 10 indicates
the iron itself, certain features of which
will be briefly described. It comprises a
heavy lower plate 10^a and a heavy upper
60 plate 10^b between which the electrical heat-
ing element properly insulated is placed,
these plates being held together by bolts
such as 10^c. The cover or shell 10^d of the
iron is secured to said plates by screws 10^e
which engage threaded openings in said
bolts, these screws serving also to secure
the handle to the iron. The ends of the
heating element of the iron are connected
65 to contact plugs 11 which project rear-
wardly from the heel of the iron. These
plugs are rigidly held in place between two
transverse plates 10^f, 10^g, the meeting faces
70 of which are cut out to receive the plugs
which are surrounded by suitable insulated
material. The plates 10^f, 10^g, are rigidly
secured by suitable screws 10^h in a recess
75 formed in the rear ends of the plates 10^a, 10^b.
A guard plate 12 is attached to the shell of
the iron above the plugs 11 for the purpose
hereinafter pointed out.

The heating stand, designated generally
by the numeral 13, is preferably made double
to hold two irons as shown in Figure 1 but
it may of course be made single if desired.
A casing 14 is secured to the rear edge of the
80 stand in any suitable manner and in this
casing the electrical mechanism of the stand
is arranged. The casing has a cover plate
14^a enclosing the rear thereof. The elec-
trical mechanism is the same for both sides
85 of the stand and a description of one will
apply to both. A block 15, preferably
formed of insulating material, is placed in
the casing 14. This block has a central por-
tion which projects upwardly from the bot-
90 tom of the casing and the upper corners of
the same is provided with rounded lugs or
projections 15^a. On each side of this cen-
tral portion the block 15 is cut away as at
95 15^b to form recesses to receive the movable
switch members hereinafter described. The
end portion 15^c of the block 15 extends up-
wardly toward the top of the casing 14, be-
ing overlaid by two short blocks or strips
100 16 of insulating material. The block 15 is
arranged between two strips of insulating
material 17 and 18 placed within the cas-
ing 14.

The mechanism for completing the cir-
cuit through the heating element of the
110

iron includes two movable switch members or hammers 20 and suitable stationary contacts 21. The movable switch members 20 are so formed as to hook over and be supported upon the curved lugs 15^a of the block 15, each of such members 20 near the end having a curved seat 20^a which is adapted to fit over said lugs 15^a. The upper end of each of the switch members 20 is provided 10 on its upper face with a curved surface 20^b which form seats for receiving the plugs 11 of the iron and at its lower end each of the members 20 is provided on its upper face with inclined contact surfaces 20^c which 15 are adapted to cooperate with spring arms 21^a of the contacts 21, these latter contacts being rigidly secured to the blocks 16 of insulating material.

As will be noted the lower ends of the 20 switch members or hammers 20 are made heavy or massive so that they will normally lie in the position indicated at the right in Figure 2 and free from the contacts 21. It will be understood that the stationary contacts 21 at the opposite ends of the block 15 are connected to the two terminals of an electric circuit. Thus the inner contact 21 is connected to the terminal 23 by means of a conductor 24 and the outer contact is connected to the terminal 25 by means of a conductor 26. These conductors are preferably mounted in grooves in the block 15 and insulated from the surrounding metallic parts of the casing.

35 The top portion of the casing is cut away to form two openings 14^b directly above the upper ends of the switch members 20, these openings permitting the plugs 11 of the iron to be easily placed on the seats 20^b of said members. The guard plate 12 of the iron is so positioned that it will lie above the openings 14^b when the iron is placed on the stand thus preventing accidental access to the plugs 11 or the switch members 20 when 40 the iron is on the stand and current flowing therethrough.

Briefly describing the operation of the device, when the iron is placed on the stand in proper position the plugs 11 will rest on the 50 upper ends of the switch members 20 and the weight of the iron will move said members about their points of support bringing the surfaces 20^c thereof into engagement with the contacts 21 on both sides. Current will 55 then flow through the heating element of the iron and at such time the guard plate 12 will cover the openings 14^b so that access to the plugs 11 or switch members 20 will be impossible. When the iron is lifted from 60 the stand the lower ends of the switch members 20 will drop by gravity out of engagement with the contacts 21, thus automatically breaking the circuit.

It will be apparent that the switch members or hammers 20 are of such shape that

they may be easily made by casting, thus avoiding expensive machine operation and skillful workmanship. Furthermore, these members are of such size as to be strong and durable so that they will not be broken 70 by accidental falling of the iron on the same or in any other way. It will also be apparent that in placing the iron on the stand, contact will be made between the plugs 11 and the members 20 before it is made between these members and the stationary contacts 21. Likewise in removing the iron from the stand the circuit will first be broken between the switch members 20 and the contacts 21. The result is that any arcing that occurs will take place between the contacts 21 and the switch members 20 but the shape and size of these members is such that the arcing will have no injurious effect.

Various modifications may of course be made in the details of the construction without departing from the spirit of the invention which is not limited to the particular embodiment herein described.

Having thus described the invention what is claimed as new and desired to be secured by Letters Patent is:

1. In combination with a sad iron or the like having a contact plug thereon, a heating stand therefor, a stationary contact in said stand, a movable switch member pivotally supported intermediate its ends on said stand, said member having at one end a portion adapted to contact with said plug and receive the weight of the iron when placed on the stand, whereby said member is moved about its pivotal support, said member having at its other end a part adapted to engage said stationary contact when the member is moved by the weight of the iron, the last named end of said member being weighted to cause the same to drop by gravity out of engagement with said stationary contact when the iron is removed from the stand.

2. A heating stand for electric irons or the type having a heating element therein and a contact plug connected to said element, said stand having a stationary electric contact mounted thereon, and means for completing an electric circuit between said stationary contact and the contact plug on the iron when the iron is placed on the stand, said means comprising a rigid switch member pivotally supported intermediate its ends on a stationary part of said stand, said switch member having at one end a part adapted to engage with the contact plug on the iron and receive the weight of the iron placed on the stand, whereby said switch member is moved about its pivotal support, said switch member having at the other end a part adapted to engage said stationary contact when the switch member is moved by the weight of

the iron, the last named end of said switch member being weighted to cause the same to drop by gravity out of engagement with said stationary contact when the iron is removed from the stand.

3. In combination with an electric sad iron or the like having an electric contact plug thereon, a heating stand for the same, a stationary electric contact on said stand, means for completing the circuit between said stationary contact and the plug on the iron when the iron is placed on the stand, said means comprising a switch member pivotally supported intermediate its ends on a stationary part of said stand, one end of said member having a part adapted to be engaged by said plug and to support the weight of the iron when the iron is placed on the stand, whereby said member is moved about its pivotal support, the other end of said member having a part adapted to engage said stationary contact when said member is moved by the weight of the iron, the last named end of said member being weighted whereby the same is disengaged by gravity from said stationary contact when the iron is removed from the stand.

4. In combination with an electric sad iron or the like having an electric contact plug thereon, a heating stand therefor, said stand having a stationary electric contact thereon, means for completing a circuit between said plug and stationary contact when the iron is placed on the stand, said means comprising a rigid switch member pivotally supported intermediate its ends on a stationary part of said stand, said member having on one end a seat for receiving said plug when the iron is placed on the stand and on its other end a part adapted to engage said stationary contact, the last named end of said member being weighted to cause the same to be automatically disengaged from said stationary contact.

5. In combination with an electric sad iron or the like having two electric plugs thereon, a heating stand for the same, said stand having two stationary electric contacts thereon forming the terminals of an electric circuit, means for electrically connecting said contacts and plugs when an iron is placed on the stand, said means comprising two independently movable switch members, each pivotally supported intermediate its ends on a stationary part of said stand, each of said members having a seat on one end upon which one of said plugs is adapted to rest, said members being movable about their points of support by the weight of the iron when said plugs rest upon said seats, each of said members having on its other end a part adapted to engage one of said stationary contacts, when said members are moved by the weight of the iron, the last named ends of said members being

weighted to cause the same to drop by gravity out of engagement with said stationary contacts when the iron is removed from the stand.

6. In combination with an electric sad iron or the like having a heating element and two contact plugs connected therewith, a heating stand therefor having two stationary electrical terminals thereon, means for electrically connecting said terminals with said plugs when the iron is placed on the stand, said means comprising two independent switch members each pivotally supported intermediate its ends on a stationary part of said stand, said switch members having seats adapted to engage said plugs and receive the weight of the iron, said members being movable about their points of support by the weight of the iron when placed on the stand, said switch members also having surfaces adapted to engage said stationary terminals when the same are moved by the weight of the iron, said members being weighted to cause the same to drop by gravity out of engagement with said terminals when the iron is removed from the stand.

7. In a heating stand for electric sad irons or the like, a casing secured to said stand, two stationary electric contacts in said casing, two independent switch members adapted to be brought into engagement with said contacts, each of said members being pivotally supported intermediate its length on a stationary part of said stand, each of said members having a seat on one end thereof and a surface on the other end, said surfaces being arranged to engage said stationary contacts when said members are moved about their points of pivotal support, the last named ends of said members being weighted whereby the same are normally maintained by gravity out of engagement with said contacts, the ends of said members which are provided with seats being arranged adjacent each other to receive contact plugs on an iron placed on the stand.

8. In a heating stand for electric sad irons or the like, a casing secured to said stand, two stationary electric contacts in said casing, two independent movable switch members arranged between said contacts, each of said switch members being pivotally supported intermediate its ends on a stationary part of said stand, each of said switch members having one end arranged to engage one of said contacts when pressure is applied to the other end thereof, the first named end of each of said members being weighted whereby the same will automatically drop out of engagement with the stationary contact when the pressure on the other end is removed.

9. In a heating stand for electric irons or

- the like, a casing secured to said stand, a switch supporting block in said casing, a stationary electrical contact on each side of said block, two independent switch members 5 pivotally supported intermediate their ends on said block, each of said switch members having one end thereof arranged to engage one of said contacts when pressure is applied to the other end, the first named end of 10 each of said members being weighted whereby the same will automatically drop out of engagement with the stationary contact when the pressure on the other end is removed.
- 15 10. In combination with an electric iron having two contact plugs thereon, a heating stand, a casing secured to said stand and having openings into which said plugs may be inserted, two stationary electrical contacts in said casing, two movable switch members in said casing, each of said members being pivotally supported intermediate its ends on a stationary part of said casing, said members having their upper ends 20 arranged adjacent said openings, and in position to be engaged by said plugs when an iron is placed on the stand, the lower ends of said members being arranged to move into engagement with said stationary contacts when pressure is applied to the upper ends thereof, the lower ends of said members being weighted to cause the same to move by gravity out of engagement with said stationary contacts.
- 25 11. In combination, an electric sad iron having two contact plugs projecting therefrom, a guard plate arranged above said plugs, a heating stand for said iron, a casing secured to said stand and having openings 30 to receive said plugs, said guard plate being positioned to cover said openings when the iron is placed on the stand, and means in said casing for automatically connecting said plugs to the terminals of an electric circuit when the iron is placed on the stand.
- 35 12. In combination with an electric sad iron having two contact plugs, a heating stand therefor, two independent pivotally supported switch members on said stand 40 said members having their upper ends positioned to be engaged by said plugs when the iron is placed on the stand, said members being movable about their points of support by the weight of the iron when placed on 45 the upper ends thereof, stationary contacts on said stand adapted to be engaged by the lower ends of said members when the same
- are moved by the weight of the iron, the lower ends of said members being weighted to cause automatic disengagement of the same 50 from said contacts.
13. A heating stand for electric irons of the type having a heating element therein and a contact plug connected to said element said stand having a stationary electric contact mounted thereon, and means for completing an electric circuit between said stationary contact and the contact plug on the iron when the iron is placed on the stand, 55 said means comprising a rigid switch member pivotally supported intermediate its ends on a stationary part of said stand, said switch member having at one end a part adapted to engage with the contact plug on the iron and receive the weight of the iron placed on the stand, whereby said switch member is moved about its pivotal support, said switch member having at the other end a part adapted to engage said stationary contact when the switch member is moved by the weight of the iron, and means for 60 automatically causing said switch member to be disengaged from said stationary contact when the iron is removed from the stand.
14. A heating stand for electric irons of the type having a heating element therein and two contact plugs connected to said element, said stand having two stationary electric contacts mounted thereon, and means for completing an electric circuit between each of said stationary contacts and one of the contact plugs on the iron when the iron is placed on the stand, said means comprising two independent switch members each 65 pivotally supported intermediate its ends on a stationary part of said stand, each of said members having at one end a part adapted to engage with one of the contact plugs of the iron and receive the weight of the iron placed on the stand, whereby said switch members are moved about their pivotal points of support, each of said switch members having at its other end a part adapted to engage one of said stationary 70 contacts when such members are moved by the weight of an iron placed on the stand, and means for automatically causing said switch members to be disengaged from said stationary contacts when the iron is removed from the stand.
